(57) CLAIM

The ornamental design for a disco ball cowboy hat, as shown and described.

DESCRIPTION

FIG. 1 is a top perspective view of the disco ball cowboy hat, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are for the purposes of illustrating portions of the disco ball cowboy hat, which form no part of the claimed design.

1 Claim, 8 Drawing Sheets
